US0D1099253S

(12) **United States Design Patent** (10) **Patent No.:** **US D1,099,253 S**
(45) **Date of Patent:** **** Oct. 21, 2025**

(54) **FIREARM**

(71) Applicant: **HS Produkt D.O.O.**, Karlovac (HR)

(72) Inventors: **Dubravko Jagunić**, Ozalj (HR);
Stephen H. McKelvain, Geneseo, IL (US); **Dennis J. Reese**, Geneseo, IL (US); **Benjamin Boyd McKelvain**, Geneseo, IL (US); **Anthony Kiel**, Davenport, IA (US); **Robert Leatham**, Mesa, AZ (US)

(73) Assignee: **HS Produkt D.O.O.**, Karlovac (HR)

(**) Term: **15 Years**

(21) Appl. No.: **29/915,371**

(22) Filed: **Oct. 30, 2023**

(30) **Foreign Application Priority Data**

Apr. 28, 2023 (HR) D20230050A

(51) **LOC (15) Cl.** **22-01**

(52) **U.S. Cl.**

USPC **D22/104**

(58) **Field of Classification Search**

USPC D22/104, 108; D21/573-574

CPC F41C 3/14; F41C 3/16; F41C 3/04; A63H 5/04; A63H 33/18

(57) **CLAIM**

The ornamental design for a firearm as shown and described.

DESCRIPTION

FIG. 1 is a left, front perspective view of the firearm;
FIG. 2 is a left, rear perspective view of the firearm;
FIG. 3 is a right, bottom perspective view of the firearm;
FIG. 4 is a right side view of the firearm;
FIG. 5 is a left side view of the firearm;
FIG. 6 is a front view of the firearm;
FIG. 7 is a bottom view of the firearm; and,
FIG. 8 is a top view of the firearm.

The broken lines illustrate portions that form no part of the claimed design. The interrupted lines illustrate portions where length forms no part of the claimed design.

1 Claim, 8 Drawing Sheets
